US0D1025555S

(12) United States Design Patent (10) Patent No.: US D1,025,555 S
(45) Date of Patent:  May 7, 2024

(54) SANDAL

(71) Applicant: Birkenstock IP GmbH, Linz (DE)

(72) Inventor: Manolo Blahnik, London (GB)

() Term: 15 Years

(21) Appl. No.: 35/514,039

(22) Filed: Dec. 27, 2021

(80) Hague Agreement Data

Int. Filing Date: Dec. 27, 2021

Int. Reg. No.: DM/219922

Int. Reg. Date: Dec. 27, 2021

Int. Reg. Pub. Date: Apr. 15, 2022

(30) Foreign Application Priority Data

Jun. 30, 2021 (EM) 008598825

(51) LOC (14) Cl. 02-04

(52) U.S. Cl.

USPC D2/916

(58) Field of Classification Search

USPC D2/896–900, 902–908, 916–918, 946,
D2/951, 969, 972–974

CPC A43B 3/12; A43B 3/10

See application file for complete search history.
